Primary Examiner—Lisa P. Lichtenstein
Attorney, Agent, or Firm—Nixon & Vanderhye[57] **CLAIM**

The ornamental design for an “aroma therapy dispenser”, as shown and described.

DESCRIPTION

FIG. 1 is a top and front perspective view of an aroma therapy dispenser according to my design;
FIG. 2 is a side and bottom perspective view thereof;
FIG. 3 is a top and right side perspective view thereof;
FIG. 4 is a top plan view;
FIG. 5 is a bottom plan view;
FIG. 6 is a front elevational view thereof, the rear being substantially identical to that shown except for the location of the side tab;
FIG. 7 is an elevational view with the dispenser rotated between the front and left side; and,
FIG. 8 is a right side elevational view thereof, the left side being substantially identical to that shown except for the location of the side tab.
